UNITED STATES PATENT OFFICE.

EDWARD F. GOLTRA, OF ST. LOUIS, MISSOURI.

DESIGN FOR A CAR-BODY BOLSTER.

SPECIFICATION forming part of Design No. 29,935, dated January 3, 1899.

Application filed December 13, 1898. Serial No. 699,184. Term of patent 14 years.

To all whom it may concern:

Be it known that I, EDWARD F. GOLTRA, a citizen of the United States, residing in St. Louis, in the State of Missouri, have invented and produced a certain new and useful Design for Car-Body Bolsters; and I do hereby declare the following to be a full, clear, and exact description of the invention, such as will enable others skilled in the art to which it appertains to make and use the same.

My invention relates to a new and useful design for car-body bolsters and is shown in the accompanying drawings, wherein—

Figure 1 represents a top plan view of a car-body bolster embodying the design. Fig. 2 represents a bottom plan view, Fig. 3 a side elevation, and Fig. 4 an end view thereof. Figs. 5, 6, and 7 represent sections on the lines 5 5, 6 6, and 7 7, respectively.

The main body portion of the bolster, comprising the central web *a*, the upper flange *b*, and the lower flange *c*, is of general I-beam shape in cross-section. It is deeper at its middle or center bearing *d* and gradually tapers past the side bearings *f* toward the ends. 25 The upper flange *b* is widened out at intervals to form the wings or extensions *n*.

I claim—

The design for a car-body bolster, substantially as herein shown and described. 30

In testimony whereof I affix my signature in presence of two witnesses.

EDWARD F. GOLTRA.
